Primary Examiner—Stella M. Reid*Assistant Examiner*—Susan E Krakower(74) **Attorney, Agent, or Firm**—Davis Bujold & Daniels, P.L.L.C.(57) **CLAIM**

We claim the ornamental design for a silicone spout, as shown and described.

DESCRIPTION

FIG. 1 is a rear perspective view of a silicone spout embodying our new design;

FIG. 2 is a front perspective view thereof;

FIG. 3 is a front elevational view thereof;

FIG. 4 is a bottom plan view thereof;

FIG. 5 is a top plan view thereof;

FIG. 6 is a left side elevational view thereof;

FIG. 7 is a right side elevational view thereof; and,

FIG. 8 is a rear elevational view thereof.

The broken lines showing the spout opening are intended for the purpose of showing structure that is not part of the design but necessary to show the environment with which the design is associated.
